ILLUMINATED BUBBLE LEVEL

Edward F. Flint, Rochester, N. Y., assignor to
 Bausch & Lomb Optical Company, Rochester,
 N. Y., a corporation of New York

Application January 28, 1942, Serial No. 428,583

7 Claims. (Cl. 240—6.44)

This invention relates to bubble levels and more particularly it has reference to illuminated bubble levels such as are adapted for use in sextants, octants and the like.

One of the objects of my invention is to provide improved means for illuminating a bubble level. Another object is to provide a bubble level having simple yet efficient means for uniformly illuminating the bubble thereof. A further object is to provide a bubble level having efficient means for providing dark-field illumination of the bubble. These and other objects and advantages reside in certain novel features of construction, arrangement and combination of parts as will hereinafter be more fully explained and pointed out in the appended claims.

Referring to the drawing:

Fig. 1 is a top plan view of a bubble level, embodying my invention, with parts broken away.

Fig. 2 is a vertical sectional view thereof.

Fig. 3 is a fragmentary sectional view taken on line 3—3 of Fig. 1.

Fig. 4 is a plan view of the light transmitting member.

A preferred embodiment of my invention is disclosed in the drawing wherein 10 indicates a housing having a central opening 11 extending therethrough. An inwardly projecting boss 12 provides a seat against which is held the upper transparent member 13 by means of a threaded lock ring 14 and a gasket 15 and a lower transparent member 16 is held against the boss 12 by the threaded lock ring 17 and gasket 18. The transparent members may be formed of any suitable transparent material such as glass or plastic and their surfaces may be plane or formed with any desired curvature. There is thus formed between the members 13 and 16 a chamber 19 which is adapted to contain a liquid 20, such as xylol, having therein a bubble 21. The size of the bubble may be controlled by adjustable diaphragm means contained in housing 22, although the details of such means are not shown since they form no part of the present invention.

Illumination of the bubble 21 is provided by a layer of luminescent material 23 which is applied as an annular border around the outer peripheral portion of the outer surface of member 16. The layer of material is applied directly to the surface of the member 16 so that it is in optical contact therewith. Although the layer 23 may, under certain conditions, provide sufficient illumination for the bubble 21, it may be desirable to apply an additional layer of

5 luminescent material 24 in optical contact with the outer surface of member 13. The layers of material 23 and 24 may comprise radium paint which is self-luminous or they may comprise phosphorescent paint which emits light following excitation by a light source.

If the layers of material 23 and 24 comprise phosphorescent material, it is, of course, necessary to provide a source of light rays for activating the phosphorescent material. On the other hand, if a self-luminous material, such as radium paint, is employed, it is not absolutely essential to employ a light source for exciting the material. However, a material such as radium paint usually comprises a phosphorescent substance, such as zinc sulphide, and a radioactive substance which activates the phosphorescent substance. Hence, if it is desired to increase the illumination produced by radium 15 paint, it may be accomplished by exposing the paint, and its constituent phosphorescent substance, to light rays from another source.

In a preferred construction, therefore, the layers of material 23 and 24 are made of radium paint which is preferably also activated by light rays emanating from another source, such as an electric lamp 25 mounted in the housing 10. Mounted directly below the layer 23, and extending substantially coextensively therewith, is the annular light transmitting member 26 having a projection 27 which is frictionally held in a slot 28 in housing 10 so as to support the member 26 in position so that light rays from lamp 25 may enter the projection 27 and pass 20 around the member 26. The member 26 and the projection 27, which may be either integral with or cemented onto the member 26, may be formed of any suitable light transmitting material such as quartz or a clear plastic material sold under the trade-mark "Lucite." Light rays from lamp 25 enter the projection 27 and pass into the member 26 and then, by internal reflection, pass around the member 26. Due to 25 irregularities on its surface, the member 26 will glow so that light rays will emanate from all sides thereof and so will activate the luminescent material in layer 23. In order to prevent light rays from reaching the bubble 21 directly from the lamp 25 and thereby causing uneven illumination, an opaque plug 29, made of fibre or the like, is positioned in the re-entrant portion 30 30 formed in member 26 opposite the lamp 25.

Positioned beneath the transparent member 16 is a cylindrical member 31 having a flange 32 35 which is attached to the housing 10 by screws 33.

The cylinder 31 and flange 32 provide a housing for the light transmitting member 26 and since the cylinder is opaque no light rays can pass directly from the member 26 to the eye of an observer who is looking through the level. Similarly, an annular opaque shield 34 having a central aperture 35 is positioned above the layer 24 on the member 13 to prevent light rays from the layers 23 and 24 from passing directly to an observer's eye. It will be apparent, therefore, that light rays from the luminescent layers 23 and 24 will pass directly through the transparent members 13 and 16 to illuminate the wall of the bubble 21 while some rays will be reflected by the surfaces of the members and onto the wall of the bubble. Since layer 23 is activated by the member 26, some rays from layer 23 will also strike layer 24 and tend to activate it also. In order to render the illumination more uniform, the walls adjacent the three sides of member 26 are also coated with layers of luminescent material 36 such as zinc sulphide or the like.

It will be apparent, therefore, that light rays will strike the wall of the bubble 21 and since no light rays reach the observer's eye directly from the illuminating means, the illuminated bubble 21 will appear as a luminous ring on a substantially dark background. Since the vertical dimension of chamber 19 is relatively small, the bubble 21 extends from the inner surface of one transparent member to that of the other. Such a construction is advantageous in instruments such as sextants or octants, since it permits an observer to look through the bubble without the distortion which is present when a bubble is bounded on its under side by an amount of liquid. With my improved illumination system, such a bubble appears as a sharply defined luminous ring on a dark background as the wall portions of the bubble in contact with the surface of the member 13 will reflect a relatively large number of the light rays while the wall of the bubble in contact with the surface of the member 16 will refract much of the incident light into the eye of the observer. Since the layers of luminescent material 23 and 24 are in optical contact with the surfaces of members 13 and 16, the rays from the layers pass into the members without losses by reflection which would otherwise occur if the layers were not in optical contact with the transparent members.

From the foregoing, it will be apparent that I am able to attain the objects of my invention and provide a bubble level having improved means for illuminating the bubble. Various modifications can obviously be made without departing from the spirit of my invention.

I claim:

1. A bubble level comprising a housing, upper and lower transparent members horizontally mounted in said housing, said members being vertically spaced apart to provide a bubble chamber therebetween, liquid in said chamber and a bubble in said liquid, said bubble extending from one member to the other member, and means for illuminating said bubble comprising a border of luminescent material positioned on the outer face of one of said members and means for exciting said material, said material being in optical contact with the face of said member and the light rays emitted therefrom angularly traversing said member before striking the wall of said bubble.

2. A bubble level comprising a housing, upper

and lower transparent members horizontally mounted in said housing, said members being vertically spaced apart to provide a bubble chamber, liquid in the chamber and a bubble in the liquid, means for illuminating the bubble comprising an annular layer of luminescent material positioned on each outer face of said members and extending as borders around the edges thereof, means for exciting said layers comprising annular light conducting means positioned adjacent to and substantially coextensive with the layer on one of the members and a light source adjacent said light conducting means for supplying light rays thereto, and shielding means for preventing light rays from said layers and light conducting means from directly entering the eye of an observer looking through the level.

3. In a bubble level the combination of a housing, two vertically spaced members horizontally mounted in the housing to provide a chamber, liquid in the chamber and a bubble in the liquid, one of said members being transparent, and means for illuminating the bubble comprising an annular light transmitting member positioned adjacent the outer face of the transparent member and extending around the border thereof, a light source positioned to direct light rays into said light transmitting member, and means for producing uniform illumination of the light transmitting member comprising layers of luminescent material substantially surrounding the walls of the light transmitting member.

4. A bubble level comprising a housing, two transparent members horizontally mounted in superposed relation in said housing to provide a chamber therebetween, liquid in said chamber and a bubble in the liquid, said bubble being compressed between said members, means for illuminating the bubble comprising a layer of luminescent material in optical contact with the outer face of one of the members, said layer extending as a border around the face of the member with a free central opening through which the bubble may be viewed, means for exciting said material comprising annular light transmitting means positioned adjacent to and substantially coextensive with said layer and a light source adjacent said light transmitting means for supplying light rays thereto, and an opaque light shield positioned adjacent the other of said members, said shield having a central opening through which the bubble may be viewed.

5. A bubble level comprising a housing, spaced upper and lower transparent members spaced apart in said housing to provide a bubble chamber, liquid in said chamber and a bubble in the liquid, said bubble extending from one member to the other whereby light rays may pass through the members and the central portion of the bubble without traversing any substantial amount of the liquid, and means for illuminating the wall of the bubble comprising layers of luminescent material positioned around the outer portions of the outer faces of said members, means for activating said layers of material comprising a housing positioned below and substantially coextensive with the layer on the lower member and having its upper side open to the layer, the inner surfaces of the housing being coated with luminescent material, a light transmitting member in the housing and extending substantially coextensively therewith, and a light source adjacent the light transmitting member whereby light rays from said source will excite the luminescent material.

6. A bubble level comprising a housing, two transparent members horizontally mounted in superposed relation in said housing to provide a chamber therebetween, transparent liquid in said chamber, a bubble in the liquid, means for illuminating the bubble whereby to render it visible as a luminous ring on a dark background, said means comprising an annular layer of luminescent material positioned on and extending around the peripheral portions of the outer surface of each of said members, said layers of material being in optical contact with said surfaces, means for exciting said layers of material comprising an annular light transmitting member positioned adjacent to and extending substantially coextensive with one of said layers of material, a light source for supplying light rays to said light transmitting member, and centrally apertured shielding means for preventing light rays from the bubble illuminating means from directly reach- 20

ing the eye of an observer looking through the level.

7. A bubble level comprising a housing, two horizontally disposed transparent members carried by said housing, said members being vertically spaced apart to provide a chamber therebetween, a liquid in the chamber and a bubble in the liquid, annular layers of luminescent material carried by and in optical contact with the marginal portion of the outer faces of the transparent members, an annular member of light conducting material disposed adjacent one of said layers of luminescent material with one face thereof closely spaced from said layer, means for directing light to said annular member, and layers of luminescent material substantially surrounding the remaining faces of said light conducting member.

EDWARD F. FLINT.
